UNITED STATES PATENT OFFICE.

ARTHUR E. SMITH, OF LOS ANGELES, CALIFORNIA.

HYPODERMIC SYRINGE.

Application filed March 24, 1927. Serial No. 177,902.

This invention relates to hypodermic syringes.

The general object of my invention is to provide an improved hypodermic syringe which is adapted to receive an ampule for injection of the drug in the ampule.

A further object of my invention is to provide means for readily forming a fluid tight joint between a syringe and an ampule.

Another object of my invention is to provide a syringe having novel means for centering an ampule in the syringe.

A further object of my invention is to provide a syringe having novel means for removably holding an ampule therein.

An additional object of my invention is to provide novel means for mounting a hypodermic needle on a syringe.

A further object of the invention is to provide a novel ampule.

Other objects and advantages of the invention will be apparent from the following description taken in connection with the accompanying drawings wherein:

Fig. 1 is a central vertical section through my improved syringe showing it in an operative position.

Fig. 2 is a similar view showing the cap turned to an open position and showing the hypodermic needle partly removed from the syringe.

Fig. 3 is a fragmentary central vertical section of the loading end of the syringe showing the plunger mechanism in a retracted position.

Fig. 4 is a section taken on line 4—4 of Fig. 1, showing the cap of the syringe in a closed position.

Fig. 5 is a section taken on line 5—5 of Fig. 2, showing the cap in an open position.

Fig. 6 is an enlarged fragmentary vertical section through the discharge or needle end of the syringe.

Fig. 7 is a top plan view of the parts shown in Fig. 6.

Fig. 8 is a detail side elevation of the cap pivot post.

Fig. 9 is a section taken on line 9—9 of Fig. 8.

Fig. 10 is a central vertical section of my novel ampule used in connection with my improved syringe.

Fig. 11 is an enlarged fragmentary elevation of the discharge end of the ampule shown in Fig. 10.

Fig. 12 is a central vertical section showing a modified form of syringe showing an ampule therein, the contents of which have been discharged.

Fig. 13 is a detail side elevation of the body of my modified form of syringe, and

Fig. 14 is an enlarged central vertical section through a modified form of tip which may be used with either form of syringe.

Referring to the drawings by reference characters I have indicated my improved syringe generally at 10. This syringe is particularly designed for use with an ampule 11, shown in detail in Fig. 10. The syringe 10 comprises a body or barrel 12 having a cross bar 13 adapted for engagement by the fingers of an operator. The body 12 is also provided with a plurality of spaced viewing apertures 14.

At one end of the body 12 I provide a tip 16, shown in detail in Fig. 6. The tip 16 has a central vertical conical aperture 17 and may be secured to the body 12 in any suitable manner such as by screw threads 18. The tip 16 is adapted to position and support a hypodermic needle indicated generally at 19.

This hypodermic needle comprises a conically shaped body portion 20 adapted to be disposed in the conical aperture 17 of the tip 16. Adjacent the apex of the conical body 20 I provide a hub 21 which terminates in a screw threaded stem 22 (see Fig. 6). The body 20 is provided with a conical recess 23 which communicates with a needle 24 having an aperture 25 therethrough.

For lengthening the arc of an accidental bending of the needle 24 I provide a needle guard 26. This needle guard preferably engages the screw threaded stem 22 of the hypodermic needle as clearly shown in Fig. 6.

The upper end of the syringe barrel 12 is adapted to be closed by a cap 27. The cap 27 (Figs. 1, 2, 4 and 5) includes a hollow body portion 28 and a tubular portion 29 secured together in any desired manner as by soldering, and a top plate 30. The body 28 of the cap is adapted to be positioned over the upper end of the syringe barrel 12 and is adapted to be disengaged from the syringe barrel

by an upward movement and a shiftable movement of the tubular portion 29 about the vertical axis of a post 31 shown in detail in Fig. 8. The post 31 may be secured to the cross bar 13 in any desired manner and is provided with a pair of oppositely disposed bayonet slots 32.

For normally retaining the cap 27 in a down position I provide in the tubular portion 29 a coiled spring 33. This coiled spring 33 is adapted to operate between a transverse pin 34 secured in the post 31 and another transverse pin 35 secured in the tubular portion 29 of the cap. The pin 35 is positioned 15 to move along the bayonet slots 32.

Associated with the cap 27 I provide a plunger mechanism 36 which includes a plurality of telescopic tubular members shown as two in number at 37 and 38. The upper- 20 most of these members is secured in any desired manner to the top plate 30 inside of the body 28. The lowermost telescopic member 38 is provided with a frusto-conical tip 39 adapted to operate inside of the barrel 12 of 25 the syringe. A spring 40 is located within these tubular telescopic members and bears between the top plate 30 and the tip 39.

The plunger mechanism 36 also includes a rod 41 which is fitted within the spring 40 and 30 has a cross bar or handle 42 upon one end. This handle 42 is adapted to be engaged by the palm of an operator's hand. At the lower end of the rod 40 I provide an enlarged head 43.

My ampule 11 which is used in connection with my improved syringe and shown in detail in Fig. 10, comprises a body 44 having a tapered end portion 45 which is closed by and terminates in a breakable tip 46. The taper 40 of the end portion 45 corresponds substantially to the taper of the conical recess 23 in the hypodermic needle 19. The tip 46 may be rendered readily separable from the ampule by scoring, notching, etching, or otherwise weakening it as indicated at 47 (see Fig. 11). Intermediate the length of the tapered portion 45 and encircling it just above the scoring 47 I provide a collar 48 of rubber or other material. The outer surface of the collar 48 may also taper at approximately the same angle as does the surface of the conical recess 23 of the hypodermic needle 19.

The open end of the ampule is closed by a stopper 49 which is preferably of rubber and 55 which fits the ampule tightly, enabling it to act as a piston to expel the contents of the ampule through the tapered end portion 45 after the tip 46 has been broken therefrom as hereinafter described. The ampule is preferably 60 of a size to hold the amount of a drug necessary for one injection.

To prepare the ampule 11 for use in the syringe 10 the tip 46 is removed from the ampule at 47. The ampule is then inserted into 65 the barrel 12 of the syringe so that the tapered

end portion 45 of the ampule is positioned in the conical recess 23 of the hypodermic needle 19, the cap 27 of the syringe having been previously swung out of engagement with the barrel as previously described and shown in Fig. 2. When the ampule has been inserted in the syringe, the outer peripheral surface of the collar 48 of the ampule impinges against the surface of the conical recess 23 of the hypodermic needle and as the cap 27 is swung 75 to a closed position as shown in Fig. 1 the conical surface of the tip 39 of the lowermost telescopic member 38 abuts the upper edges of the ampule, centers it and retains it in a correct position.

To discharge the contents of the ampule the operator grasps the handle 42 and moves the plunger rod 41 inwardly until the head 43 abuts the stopper 49 of the ampule. Upon a further movement of the plunger rod and 85 head 42 the stopper will be forced towards the tapered end of the ampule acting as a piston to expel the contents of the ampule out through the hypodermic needle 19.

As pressure is applied on the plunger head 90 42 to move the stopper 49 downward the collar 48 of the ampule will be forced into very tight engagement with the conical surface of the recess 23 in the hypodermic needle 19, the more pressure required to move the stopper the tighter the collar 48 will engage the conical recess, thus creating a fluid tight seal between the ampule and the syringe. Also as pressure is applied to the stopper the ampule will, through the medium of the collar 100 48, exert pressure on the body 20 of the hypodermic needle 19 and force its outer conical surface into tight engagement with the surface of the conical aperture 17 of the tip 16, thus preventing any accidental movement 105 of the hypodermic needle.

By providing the apertures 14 in the body 12 of the syringe, sight openings are formed through which the contents of the ampule will be visible and so that the movement of 110 the stopper 49 and the extent to which the contents of the ampule have been discharged may be readily observed by the operator of the syringe.

In Figs. 12 and 13 I have shown a syringe 115 50 provided with a modified form of cap 51. The syringe 50 is similar in construction to the syringe 10 shown in Fig. 1, having a hollow tubular body or barrel 53 wherein equally spaced elongated apertures 54 are provided. A tip 56, similar to the tip 16 shown in Fig. 6, detachably engages the lower end of the barrel 53 and is provided with a conical aperture 57. A hypodermic needle 58 similar to the hypodermic needle 19 shown in Fig. 6, 120 is detachably positioned in the conical recess 57 of the tip 56. The hypodermic needle 58 comprises a body portion 58^a having a conical recess 58^b therein which communicates with a hollow tube 58^c. The cap 51 comprises a 125 130

cup shaped body portion 59 the sides of which are adapted to be positioned over the end portion of the syringe barrel 53. In the side and adjacent the lower edge of the body 59 I 5 provide an inwardly extending pin 59^a. The upper portion of the barrel 53 above the cross bar 55 is provided with a bayonet slot 60 (see Fig. 13) in which the pin 59^a of the cap 51 is adapted to actuate.

10 A plunger mechanism indicated at 61 is mounted in the cap 51 and includes a plurality of telescopic members 62 and 63. The upper telescopic member 62 is secured to the cap 51 as by soldering or in any other suitable manner and the lowermost telescopic member 63 is provided with a transverse partition 64. A spring 65 is located within these telescopic members and bears between the top of the cap and the transverse partition 20 64 of the member 63 to normally retain the member 63 in an extended position.

The plunger mechanism 61 also includes a plunger rod 66 which is fitted within the spring 65 and has a cross bar or handle 67 25 provided at one end and an enlarged head 68 provided at its other end.

When it is desired to use my modified form of syringe 50 for making an injection the cap 51 is rotated so that the pin 59^a may ride 30 in the vertical portion of the bayonet slot 60 as the cap is lifted upwardly. After removing the cap 51 an ampule 11 is inserted into the barrel 53 of the syringe after having been prepared for injecting purposes as previously 35 described. The cap is then replaced and the transverse partition 64 of the telescopic member 63 abuts the upper edge of the ampule while the lowermost portion of the member 63 surrounds a portion of the top end of the 40 ampule, thus retaining the ampule in a correct position.

To expel the contents of the ampule 11 the operator moves the handle 67 toward the cross bar 55 so that the head 68 of the plunger 45 bar 66 abuts the stopper 49 whereby upon a further movement of the handle the head 68 will move the stopper in the ampule and cause the stopper 49 to act as a piston to expel the contents of the ampule 11 out through the hollow tube 58^a of the hypodermic needle 58. As pressure is applied to the stopper 49 by the head 68 the collar 48 of the ampule will tightly engage the surface of the conical recess 58^a of the hypodermic needle 58 thus 55 creating a fluid tight seal therebetween.

In Fig. 14 I have indicated at 70 a modified form of tip which may be used in connection with either the syringe 10 shown in Fig. 1 or the syringe 50 shown in Fig. 12.

60 The tip 70 is preferably detachably secured to the lower end of the syringe barrel as by screw threads 71. The tip 70 comprises a body 72 which terminates in a screw threaded tip 73 to which a hub 74 of a hypodermic needle 75 may be secured. The body 72 is

provided with a conical recess 76 which communicates with an aperture 77 which extends through the tip 73.

When an ampule such as the ampule 11 is inserted into the barrel of the syringe for the purpose of injection the rubber collar 48 on the tapered end portion 45 of the ampule will fit within the conical recess 76 of the tip and as pressure is applied to the stopper 49 of the ampule as previously described, a fluid tight seal will be formed between the ampule and the syringe.

The lower end of the tip 16 of the syringe is preferably provided with a cylindrical portion 16^a which tightly engages the cylindrical hub 21 of the hypodermic needle 19, holding the needle tightly in place and preventing accidental dislodgment of the hypodermic needle.

From the foregoing description it will be apparent that I have provided an improved ampule and a syringe wherein novel means is provided for positioning a hypodermic needle in the syringe and wherein novel means is provided for centering and holding an ampule, and wherein means is provided for forming a fluid tight seal between the ampule and the syringe.

What I claim is:

1. A syringe of the character described comprising a barrel, a cap mounted to move on an axis parallel to and spaced laterally from the axis of said barrel, a plunger movable into said barrel through said cap, and means to hold an ampule arranged in said barrel.

2. A syringe of the character described comprising a barrel having an open top, a cap for said open top and means to mount said cap for swinging movement about an axis parallel to the axis of said barrel.

3. A syringe of the character described comprising a barrel, a cap for said barrel, spring means for normally retaining said cap in engagement with said barrel, a plunger movable into said barrel through said cap, an ampule in said barrel, a centering member secured to said cap and movable in said barrel, said ampule having an open end, said centering member including a portion smaller than the end of said ampule and adapted to engage within an ampule arranged in said barrel to center the ampule.

4. In a syringe, a barrel having a closure for one end thereof, said closure including an ampule holding member for engaging the end of an ampule, a plunger, said plunger being movable within said barrel and through said ampule holding member, a tip on said barrel, a needle on said tip, said tip having a tapered recess therein, an ampule in said barrel, said ampule including a hollow body portion and an end portion tapered to approximate the taper of said recess, a stopper in said body portion adapted to be engaged by said plunger.

er, a resilient collar adapted to fit said tapered end portion of said body, said resilient collar being of a length greater than the thickness thereof and being adapted to fit within said 5 tapered recess of said tip, whereby when pressure is applied to said ampule by said ampule holding member said resilient collar will be expanded in said recess without rolling

and will engage the wall of said recess and the tapered end portion of the ampule to form 10 a fluid tight seal between said ampule and said tip and releasable means to hold said ampule holding member in position.

In testimony whereof, I hereunto affix my signature.

ARTHUR E. SMITH.
